UNITED STATES PATENT OFFICE.

OTTO SPAHR, OF PHILADELPHIA, PENNSYLVANIA, ASSIGNOR TO STRAUSE GAS IRON CO., OF PHILADELPHIA, PENNSYLVANIA, A CORPORATION OF PENNSYLVANIA.

SADIRON.

1,340,257.

Specification of Letters Patent. Patented May 18, 1920.

Application filed November 14, 1914. Serial No. 872,061.

To all whom it may concern:

Be it known that I, OTTO SPAHR, a citizen of the United States, and resident of Philadelphia, county of Philadelphia, State of Pennsylvania, have invented certain new and useful Improvements in Sadirons, of which the following is a specification.

My invention relates to sad irons and more particularly to that type thereof commonly known as self-heating sad irons and has for its object to provide a construction which permits the handle to be moved to a position substantially outside of the effects of the heat rising or radiating from the iron when not in use without necessitating a complete detachment of said handle from the iron. My improvement will be fully described hereinafter and the features of novelty will be pointed out in the appended claims.

Reference is to be had to the accompanying drawings in which Figure 1 is a side elevation of an iron showing one form of my improved handle construction; Fig. 2 is an end view thereof; Fig. 3 is a detail section of another form of my invention; Fig. 4 is a side elevation illustrating still another form of said invention, and Fig. 5 is an end view thereof.

In the drawings 10 represents the body of a sad iron of the type commonly known as self-heating gas irons and 11 indicates the cover thereof which in most instances is made movable relatively to said body to expose the interior thereof. In the form as illustrated in Figs. 1 and 2, my improvement comprises a substantially rigid horizontal member 12 attached to the cover 11 in any suitable manner, as by means of screws 13 and forming part of or secured to an upright member 14 extending upwardly from one end thereof, the said member 12, at its other end, being continued in the form of an upwardly extending member 15^a, to the free end of which another member 15^b is pivoted or hinged at 15^c. The member 15^b, in turn, is attached to one end of a suitably shaped handle 16^a, for instance, by means of a pin or screw 17, the opposite end of said handle being arranged to be detachably secured, in its operative position, to the upright member 14 in any convenient manner. For instance, said handle 16^a may carry, at said opposite end, a lug 18^a passing through a lever 21' which projects above

the handle to form a finger piece and also extends slightly below said lug 18^a and is loosely mounted thereon. In this form the upright member 14, is simply provided with an aperture 20^a into which the lug 18^a is 60 adapted to snap and lock the handle in operative position. When it is desired to disconnect the said handle from the member 14, the finger piece of the lever 21' is pressed outwardly away from the handle end which 65 causes the lower end of said lever 21' to bear against the handle end and an intermediate portion thereof to engage the end of the member 14 so that as the outward pressure is continued, the said member 14 will 70 be forced away from said handle end and the lug 18^a in this manner released from the aperture 20^a. After this has been done the handle may be pivotally swung on the hinge 15^c to an inoperative position indicated by 75 dotted lines in Fig. 1, a suitable stop 15^d being provided for engagement by the member 15^b, whereby the swinging movement of said handle in the indicated direction is arrested. The finger piece of the lever 21' is 80 preferably provided with a button, pad or the like 22 of a material which is a poor conductor of heat and adapted to form a protection for the finger as pressure is exerted to manipulate the lever and thus prevent injury by burning to the person manipulating the iron. The lever 21' by being loosely mounted on the lug 18^a may be turned downwardly or reversed thereon, so that in this position, no portion thereof projects above 85 the handle to interfere with the ready packing of the iron for shipment or to force itself through such package.

Instead of constructing the lever 21' in one piece as in the form described, the same 95 may be made in two parts 21^a and 21^b connected by a rule joint 21^c or the like, as shown in Fig. 3, so that the portion 21^b may fold down upon the handle and thus do away with any upward projections above said 100 handle. When it is desired to release the one end of the handle, as above described, the portion 21^b is raised and pressed outwardly in the same manner as in Figs. 1 and 2, the rule joint 21^c or the like rigidly connecting the parts 21^a and 21^b and causing them to move as a unit during this movement to actuate the member 14 as will be 105 readily apparent.

As shown in Figs. 4 and 5, the lever 21 110

may be omitted and the member 14 itself be extended upwardly to form a finger piece 21^a upon which an outward pressure may be exerted to release the lug 18^a from the aperture 20^a in the same manner as in the two previous forms. This finger piece 21^a may also be provided with an insulating button, pad or the like 22 and further if desired, may be connected with the member 14 by means of a rule joint or the like similar to the joint 21^c instead of being integral and rigid therewith. In this form the handle 16, corresponding to the handle 16^a, instead of being carried by a hinge member 15^b, is carried by a resilient member 15, which, as shown, may have its one end secured to the cover 11, preferably beneath the member 12 and by means of one of the screws 13. As the handle 16 is detached from the member 14 the resiliency of the member 15 will carry said handle 16 to an inoperative position corresponding approximately to that indicated by dotted lines in Fig. 1. It will be understood that the resilient member 15 may, if desired, be substituted for the compound member 15^a, 15^b of Figs. 1 and 2 and that the latter may replace said resilient member 15 in Figs. 4 and 5 without affecting the efficiency of the constructions.

Instead of the forms shown and described, the upright member may be hinged at its lower end directly to the cover instead of being made in two parts which are hinged together, as shown and described, or the horizontal member may be so hinged and made integral with or secured to the two end members, suitable locking devices being in each case provided for locking said handle in operative position and for releasing it when it is desired to swing the handle to an inoperative position. In addition to this, if desired said handle either by itself or in conjunction with its support may swing in a plane parallel with the cover, for instance about one of the screws 13, the other screw in this case being replaced by a suitable and releasable locking device.

All of the forms of my improvement provide simple constructions in which the handle is readily shifted to an inoperative protected position by movements which are natural and easily performed and without necessitating the complete detachment of the handle from the iron, thus preventing loss or misplacing of said handle and yet securing the same beneficial results as if the handle were entirely removed from the iron body.

It will be clearly apparent that, while I have shown and described my improvements in connection with a gas iron, the same is equally well adapted for use in connection with all other types of sad irons.

Various other changes in the forms shown and described may be made within the scope

of the claims without departing from the spirit of my invention.

I claim:

1. A sad iron comprising a body, a handle having its one end movably connected therewith, said handle being movable to an inoperative position substantially outside of the heat rising from said body when not in use, a member extending upwardly from said body, means for detachably connecting the other end of said handle in an operative position to said member, and a device for moving said member away from said handle end to disconnect said connecting means whereby said end of the handle is released from said member.

2. A sad iron comprising a body, members extending upwardly therefrom, a handle having one end pivotally connected with one of said members whereby said handle is movable to a position substantially outside of the heat rising from said body when not in use, means for detachably connecting the other end of said handle in an operative position to the other member and a device for moving said other member to disconnect the connecting means whereby the one end of said handle is released.

3. A sad iron comprising a body, a member extending upwardly therefrom, a handle having one end pivotally connected with said member and arranged to be moved to a position substantially outside of the heat rising from said body when not in use, a projection at the opposite end of said handle, a second member extending upwardly from said body and provided with an aperture adapted to receive said projection and lock said handle in an operative position and means for moving said second member away from said handle to disengage said projection and aperture.

4. A sad iron comprising a body, a member extending upwardly therefrom, a handle having one end pivotally connected with said member and arranged to be moved to a position substantially outside of the heat rising from said body when not in use, a projection at the opposite end of said handle, a second member extending upwardly from said body and provided with an aperture adapted to receive said projection and lock said handle in an operative position and a lever movably mounted on said projection and arranged to press said second member away from said handle to disengage said projection and aperture.

In testimony whereof, I have hereunto set my hand in the presence of two subscribing witnesses.

OTTO SPAHR.
